STEAM IRON

Arthur A. Johnson, Bridgeport, Conn., assignor
to Casco Products Corporation, Bridgeport,
Conn., a corporation of Connecticut

Application July 18, 1950, Serial No. 174,427

17 Claims. (Cl. 38—77)

1

This invention relates to electric sadirons and particularly to sadirons of the type capable of generating steam and applying the same to the surface of material being ironed.

Irons of this character are conventionally provided with a sole plate, a water reservoir located above the sole plate and an operating handle extending along the top of the iron for manipulating the same during ironing. Various provisions have been made for filling the water reservoir in such irons, one of the most convenient of which is to have an upward-opening filling aperture at the forward, upper part of the handle which connects with a duct leading through a portion of the handle and into the reservoir. It is an object of this invention to provide such a forward, upward-opening filling aperture with a closure which prevents the accidental dropping of foreign matter into the filling passage while the iron is in use or is stored, but which is, however, readily and conveniently movable to open position by the hand in which the iron handle is held, leaving the other hand free for manipulation of the water container or tap for filling the reservoir.

Certain types of steam irons are provided with a dome which rises above the upper surface of the reservoir, in many cases the steam generating chamber, and with an open standpipe extending up into the center of said dome and leading to the steam jets of the iron. This arrangement constitutes a water trap which provides for separation of water droplets from the steam prior to its ejection. Such domes and standpipes are often arranged at the forward part of the iron and extend up into the handle. This invention has for another object the provision of a structure which will serve both as a steam dome or water trap and as a filling device so as to reduce materially the cost of the iron as compared with one in which these components are separately arranged.

It is another object of the invention to provide a relief valve mechanism for the steam generating chamber so arranged that its exhaust will be directed forwardly of the iron where it will not be dangerous to the operator and in a location where the ejected steam may be seen and indicate to the operator that the relief valve is operating.

A feature of the invention is the provision of the combined water trap and filling mechanism in such fashion that it also performs the function of the above-mentioned relief valve.

A further feature of the invention is the provision of a smoothly contoured handle which is comfortable and convenient for operating the iron, the handle having a slidable portion which

2

when slid to its primary position, forms a continuation of the smooth contours of the handle, and when slid to a secondary position, uncovers a filling aperture for the water reservoir.

5 A still further feature of the invention is the provision of a steam iron including two movable elements, one a filling aperture closure, and another a steam system seal, and means whereby opening of the former automatically opens the latter, and closing the former automatically closes and seals the latter.

10 A still further feature of the invention is the provision of a spring urged filling valve for a steam iron and a slidable operator therefor, and means interconnecting the valve and operator so arranged that the valve will be held open against its spring without maintaining pressure on the operator.

15 Additional features and advantages will hereinafter appear.

In the drawing:

Figure 1 is an elevation, partially in section, of an iron according to the invention.

20 Fig. 2 is a fragmentary top plan showing the cover portion of the handle in place.

Fig. 3 is a view similar to Fig. 2 but with the cover portion of the handle removed and taken approximately on line 3—3 of Fig. 1.

25 Fig. 4 is a detail section taken on line 4—4 of Fig. 1.

Fig. 5 is a fragmentary section similar to portions of Fig. 1, but showing the cover portion of the handle in open or filling position.

30 In Fig. 1 is illustrated an iron 10 according to the invention having a conventional sole plate 12 by which is carried the usual electric heating element 14. In the forward end of the sole plate 12 is a recess 16 which is tightly closed by a plate 18 and which forms a steam chamber for distributing

35 steam to a plurality of steam jets 20 (only one of which is shown) which pass through the forward end of the sole plate 12 and communicate with chamber 16. Mounted on the sole plate 12 is a water reservoir 22 provided interiorly with baffles such as 24, 26 and 28 for limiting movement of the contained water and preventing splashing into the steam conduction system. The tank 22 is arranged closely adjacent the upper surface of the sole plate 12 so as to receive heat readily therefrom and to act as a steam generating chamber.

40 A handle member 30 of non-conductive, heat resistant material is rigidly mounted on the upper surface of the tank 22 for transporting the iron from place to place, and for manipulating the iron during ironing. The handle 30 is smoothly

contoured to fit the operator's hand so that the iron can be used with the maximum of comfort.

The forward leg 32 of the handle member 30 is hollow and provides a recess 34 which registers approximately with an opening 36 in the upper surface of the reservoir 22. A tube 38 having an upper flare 40 is firmly sealed to the rim of the opening 36 and acts on an upwardly projecting filling funnel therefor. The tube 38 projects upwardly above the upper surface of the reservoir 22 and into the recess 34 of the handle. Preferably the flare 40 is formed after the leg 32 of handle 30 is placed over the tube 38, as by spinning or swaging, and serves as means to fix the handle to the reservoir at the forward end. The construction shown in Fig. 1 with the main portion of forward leg 32 of handle 30 spaced outwardly from tube 38 is also preferred since a minimum of surface contact is permitted in order that heat transfer to the handle shall not be excessive.

A valve or seal 42 consists of a disc-shaped member provided with a resilient sealing ring 44 of rubber-like material, and the same is capable of engaging in the flare 40 to close and seal the upper end of the tube 38. A central, upwardly extending stem 46 on the valve 42 passes slidably through a central aperture in a spider 48 firmly mounted in the recess 34 above the upper end of the tube 38. The spider includes apertures 50 to permit passage of water therethrough. A compression spring 52 surrounds the stem 46 between the spider 48 and valve 42 and urges the valve into sealing position in the flare 40, tightly closing the upper end of tube 38.

Means is also provided for lifting the valve 42 away from the flare 40 against the force of spring 52 and includes a lever 54 pivotally mounted midway of its length in a slot 56 formed in the grip portion 58 of handle member 30, by means of a pin 60. One end of the lever 54 has a pin-and-slot connection 62 with the upper end of valve stem 46, and the other end 64 thereof projects upwardly out of the groove 56, to act as a cam follower. A portion of the grip 58 of handle member 30 is not integrally formed with the rest of the grip and is slidably mounted with respect thereto for movement along the handle. This grip portion forms a combined closure for the upper end of recess 34, a manual operating member for raising valve 42 by means of lever 54, and is designated by reference character 66. Any suitable slidable mounting which retains the slid- able grip section 66 in place on the handle will serve the purpose, but a preferred form of connection is shown in the drawings wherein slotted plates 68 are firmly embedded in the main grip section 58 and are received in grooves 70 in the slid- able grip section 66, while a cross pin 72 carried by grip section 66 passes through the slots in the plates to retain the parts in place and provide limiting stops for the sliding movement. The undersurface of slidable grip section 66 is pro- vided with a cam surface 74, 76 which, by coop- erating with the projecting end 64 of lever 54 first lifts the valve 42 and then retains the same lifted as the grip section is moved rearwardly, or towards the right, as shown in the drawing, or permits the valve 42 to lower against the flare 40 as the grip section 66 is moved all the way for- ward, or to the left in the drawing.

A spring urged latch 78 automatically engages in a notch 80 to prevent movement of the grip section 66 after it has been moved forwardly all the way into grip completing position. In order

to move the grip rearwardly it is then necessary to press a release button 82 which is exposed at the upper surface of the grip section 66 in a shal- low recess 84, and which is operatively engaged with the latch 78 to release the same.

Threadedly mounted in an opening in the plate 18 and in another opening in the proximate bot- tom wall of the reservoir 22 is the lower end of a standpipe 86. Clamped between these two walls by means of said threaded connection is preferably provided a sealing member or gasket 88 which prevents any leakage of moisture around the outer surface of pipe 86 between the reservoir 22 and steam chamber 16. The standpipe 86 projects upwardly through the opening 36 and above the top surface of the reservoir 22 into the interior of tube 38. The upper end 88 of the pipe 86 is closed off, preferably by pinching or crimping, so as to prevent accidental ingress of moisture to steam chamber 16 during filling, and has side openings 90 at its upper end to form steam passages connecting the upper portion of the tube 38 with the chamber 16 and with jets 20.

The forward wall of the forward leg 32 of the handle member 30 has a vent or relief opening 92 which communicates with the recess 34 between the valve 42 and the closure portion of slid- able grip section 66 for a purpose which will herein- after appear.

In operation, assuming the iron to be in the condition illustrated in Fig. 1, and without water, the button 82 is depressed to release latch 78, and grip section 66 is slid rearwardly by the thumb of the same hand which grasps the handle 30, uncovering the upper end of recess 34 in the forward leg 32 of the handle. This rearward move- ment of the grip section also simultaneously raises and holds valve 42 away from flare 40 by the impingement of cam surfaces 74, 76 upon the upper end 64 of the lever 54. The iron is then ready for filling and has been brought to that condition by movements which can be con- ducted entirely by the hand which engages the grip portion 58 of handle 30. In the meantime the other hand of the operator may be engaged in filling the iron with the desired quantity of water.

The water is introduced through the upper end of recess 34, passes through openings 50 in spider 48, between the raised valve 42 and the flare 40, through tube 38 and into the reservoir 22. The water first engages the baffle 28 and runs from the lateral edges thereof (not shown) into the lower portions of the reservoir 22. Since the upper end of standpipe 86 is closed as shown by reference character 88, and since the openings 90 are in the sides thereof, the danger of intro- ducing water into the standpipe during filling is removed.

When filling of the iron is completed, the thumb of the hand which grasps the grip portion 58 is moved forward to slide the grip section 66 forward. As the end 64 of lever 54 leaves the flat section 76 of the cam surface, valve 42 is no longer retained in open position. Further move- ment forward permits the end 64 of lever 54 to travel upward along the sloping cam face 74 and finally, valve 42 closes tightly against flare 40 under the influence of spring 52. At the same time, the grip section 66 moves forward until it closes the upper end of recess 34 to prevent inadvertent dropping of any foreign matter into the filling system while the iron is in use or stored, and until the iron is ready for emptying or for another refilling. As the grip section 66 moves

to final closing position, the latch 78 snaps into the recess 80 to retain the grip section in forward position.

Passage of electric current through the element 14 in the conventional manner causes the sole plate 12 to heat up and thus raises the temperature of the water in reservoir 22. When the temperature becomes sufficiently high, steam is driven off from the upper surface of the water, passes around the baffles 24, 26 and 28, up into the tube 38, through openings 90 into the standpipe 86 and downwardly into steam chamber 16 from whence it is ejected by jets 20 onto the material being ironed. From this it can be seen that, with the valve 42 closing its upper end, the filling tube 38 becomes a steam dome cooperating with the standpipe 86 to provide a trap which prevents water droplets from reaching the steam jets 20.

In case any of the steam passages, such as jets 20, should somehow become clogged, and cause a rise of pressure to occur in the reservoir 22, the invention also serves the purpose of a relief or safety valve. When the steam pressure becomes sufficient to overcome the force of spring 52, the valve 42 raises slightly and relieves the pressure, allowing the steam to escape through exhaust opening or vent 92. This opening is located in the front portion of the front leg 32 of handle 30 so as to be directed generally away from the operator at all times to avoid the possibility of injury or discomfort. The forward location of the opening 92 is also such that a slight cloud of condensing steam issuing therefrom will quickly catch the eye of the operator and give prompt warning of the improper functioning of the iron.

From the foregoing description it can be seen that the invention provides an economical structure for a steam iron which combines the functions of a steam dome or water trap, a filling mechanism, and a relief valve. Furthermore, the parts are conveniently arranged at the forward part of the iron so that filling can take place conveniently through the forward upper part of the handle, and the relief valve exhaust can be forwardly directed in a conspicuous, yet harmless direction.

Furthermore a novel handle is provided such that a section 66 thereof is slidable to two positions. In the first position the section completes a smoothly contoured comfortable handle suitable for ironing, and at the same time closes the filling system of the iron to prevent access of foreign matter thereto. In the second position it opens the filling system for the introduction of water. In addition the slideable portion of the handle is interconnected with a steam dome closure valve so as to open and close the same automatically in response to sliding of the handle section. The slideable section 66 of the handle is so located as to be conveniently operated by the thumb of the hand which carries the iron, thereby leaving the other hand free to perform the manipulation of other devices necessary to the filling operation.

Variations and modifications may be made within the scope of the claims and portions of the improvements may be used without others.

I claim:

1. A steam iron having a base assembly including a heated sole plate and a water reservoir; a handle mounted on and above said base assembly for carrying and manipulating the iron, said handle being formed with a vertical member provided with an upright filling passage there-

through and having an open top, the other end of the passage communicating with said reservoir; a valve seat in said passage remote from the upper open end thereof; a closure valve movably mounted in said passage and resiliently engaging said valve seat; a closure on the handle for closing the open end of the filling passage; and means for mounting the closure for lateral movement away from position above the open end of the filling passage to provide, while the base assembly is in substantially horizontal position, unobstructed access to the filling passage for the free fall of water into the passage and through the passage past the valve into the reservoir when the valve is open.

2. The invention as defined in claim 1 in which there is means connecting the closure and the closure valve for co-ordinate movement between open and closed positions.

3. In a steam iron, a base assembly including a heated sole plate and a water reservoir; a handle mounted on and above said base assembly for carrying and manipulating the iron, said handle having an upright post formed with an elongate filling passage therethrough having one end in communication with said reservoir; a valve mounted on said handle within said filling passage and movable axially along the passage between an open position, and a closed position providing tight sealing interruption for said filling passage at a point intermediate the ends thereof; a manually movable operating member mounted on said handle for movement longitudinally of the handle and laterally with respect to said post; means interconnecting said operating member and said valve for causing movement of the latter in response to manual movement of the former; and means operable in response to movement of said operating member for closing and opening the other end of said filling passage as said valve is moved to sealing and non-sealing positions respectively.

4. In a steam iron, a base assembly including a heated sole plate and a water reservoir; a handle mounted on and above said base assembly for carrying and manipulating the iron, said handle being formed with an elongate filling passage therethrough having one end in communication with said reservoir; a valve mounted on said handle within said filling passage and movable between an open position, and a closed position providing tight sealing interruption for said filling passage at a point intermediate the ends thereof, said valve operating in such a direction that steam pressure within the reservoir tends to force the valve in an opening direction; resilient means for urging said valve in a closing direction; a manually movable operating member mounted on said handle; means interconnecting said operating member and said valve for causing movement of the latter in response to manual movement of the former; means operable in response to movement of said operating member for closing and opening the other end of said filling passage as said valve is moved to sealing and non-sealing positions respectively; and normally open venting means for the portion of said filling passage between said valve and said passage closing means.

5. In a steam iron, a base assembly including a heated sole plate and a water reservoir; a handle mounted on and above said base assembly for carrying and manipulating the iron, said handle being formed with an elongate filling passage therethrough having one end in communication

with said reservoir; a valve mounted on said handle within said filling passage and movable between an open position and a closed position providing tight sealing interruption for said filling passage at a point intermediate the ends thereof, said valve operating in such a direction that steam pressure within the reservoir tends to force the valve in an opening direction; resilient means for urging said valve in a closing direction; a manually movable operating member mounted on said handle; means interconnecting said operating member and said valve for causing movement of the latter in response to manual movement of the former; means operable in response to movement of said operating member for closing and opening the other end of said filling passage as said valve is moved to sealing and non-sealing positions respectively; and normally open forwardly directed venting means for the portion of said filling passage between said 20 valve and said passage closing means.

6. In a steam iron, a base assembly including a heated sole plate provided with a steam jet and a water reservoir, said reservoir having a tubular upward extension at the forward end thereof; a handle mounted on and above the base assembly for carrying and manipulating the iron, said handle having a passage therethrough receiving said upward extension and opening at the top of said handle; a movable valve carried by said handle within said passage, engageable with the upper portion of the extension for opening and closing the bore in said extension, said valve being displaceable from said upper portion by excess steam pressure to relieve the same; and a standpipe mounted on said base assembly, communicating with said jet, and extending upwardly through said reservoir into said tubular extension, said standpipe having an opening adjacent its upper end.

7. In a steam iron, a base assembly including a heated sole plate provided with a steam jet and a water reservoir, said reservoir having an apertured tubular upward extension at the forward end thereof; a handle mounted on and above the base assembly for carrying and manipulating the iron, said handle having a passage therethrough receiving said upward extension and opening at the top of said handle; a valve carried by said handle within said passage, said valve being movable upwardly away from the upper end of said extension to open the aperture thereof, and downwardly towards said extension to close said aperture; and a standpipe mounted on said base, communicating with said jet and extending upwardly through said reservoir into said tubular extension having its upper end closed, and openings formed in the sides thereof within said tubular extension.

8. In a steam iron, a base assembly including a heated sole plate and a water reservoir; and a smoothly contoured handle comprising two parts, one of said parts being mounted on and above the base assembly and having a generally horizontal portion for carrying and manipulating the iron and a vertical post provided with a passage therethrough communicating with said reservoir, the other part being a movable grip section; means mounting the grip section on said horizontal portion of the handle for horizontal movement between a first position overlying said post in which it forms a smooth continuation of said horizontal portion and closes the upper end of said passage, and a second position exposing the upper end of said passage.

9. In a steam iron, a base assembly including a heated sole plate and a water reservoir; a smoothly contoured handle comprising two parts, one of said parts being mounted on and above the base assembly and having a generally horizontal portion for carrying and manipulating the iron and a vertical post provided with a passage therethrough communicating with said reservoir, the other part being a movable grip section; means mounting the grip section on said horizontal portion of the handle for horizontal movement between a first position overlying said post in which it forms a smooth continuation of said horizontal portion and closes the upper end of said passage, and a second position exposing the upper end of said passage; and releasable latch means for retaining said grip section in said first position.

10. In a steam iron, a base assembly including a heated sole plate and a water reservoir; a smoothly contoured handle comprising two parts, one of said parts being mounted on and above the base assembly and having a generally horizontal portion for carrying and manipulating the iron and a vertical post provided with a passage therethrough communicating with said reservoir, the other part being a movable grip section; means slidably mounting the grip section on said horizontal portion of the handle for forward horizontal movement to a first position overlying said post in which it forms a smooth continuation of said horizontal portion and closes the upper end of said passage, and for rearward movement to a position exposing the upper end of said passage; and releasable latch means for retaining said grip section in said first position.

11. In a steam iron, a base assembly including a heated sole plate and a water reservoir; a smoothly contoured handle comprising two parts, one of said parts being mounted on and above the base assembly and having a generally horizontal portion for carrying and manipulating the iron and a vertical post provided with a passage therethrough communicating with said reservoir, the other part being a movable grip section; means mounting the grip section on said horizontal portion of the handle for horizontal movement between a first position overlying said post in which it forms a smooth continuation of said horizontal portion and closes the upper end of said passage, and a second position exposing the upper end of said passage; a valve mounted on said handle within said passage and movable vertically between a first position in which the passage is interrupted by the valve and a second position in which the valve does not interrupt the passage; and means interconnecting said grip section and valve for causing vertical movement of the latter to its first position in response to horizontal movement of the grip section to its first position, and vertical movement to its second position in response to horizontal movement of the grip section to its second position.

12. In a steam iron, a base assembly including a heated sole plate and a water reservoir, said sole plate having a steam jet formed therein; a smoothly contoured handle comprising two parts, one of said parts being mounted on and above the base assembly for carrying and manipulating the iron, and having a vertical passage therethrough communicating with said reservoir, the other part being a movable grip section mounted on said first part of the handle for movement between a first position in which it forms a smooth continuation of said first part

and closes the upper end of said passage, and a second position exposing the upper end of said passage; a standpipe mounted on said base assembly, communicating with said jet, and extending upwardly into said passage; a valve mounted on said handle within said passage and movable between a first position in which the passage is interrupted by the valve just above the upper end of said standpipe, and a second position in which the valve does not interrupt the passage; and means interconnecting said grip section and valve for causing movement of the latter to its first position in response to movement of the grip section to its first position, and to its second position in response to movement of the grip section to its second position.

13. In a steam iron, a base assembly including a heated sole plate and a water reservoir, said sole plate having a steam jet formed therein; a smoothly contoured handle comprising two parts, one of said parts being mounted on and above the base assembly for carrying and manipulating the iron, and having a vertical passage therethrough communicating with said reservoir, the other part being a movable grip section mounted on said first part of the handle for movement between a first position in which it forms a smooth continuation of said first part and closes the upper end of said passage, and a second position exposing the upper end of said passage; a standpipe mounted on said base assembly, communicating with said jet, and extending upwardly into said passage; a valve mounted on said handle within said passage and movable between a first position in which the passage is interrupted by the valve just above the upper end of said standpipe, and a second position in which the valve does not interrupt the passage; means interconnecting said grip section and valve for causing movement of the latter to its first position in response to movement of the grip section to its first position, and to its second position in response to movement of the grip section to its second position; and resilient means urging said valve to its first position, said one handle part having a vent opening communicating with said passage between said valve and the upper end of the passage.

14. In a steam iron, a base assembly including a heated sole plate and a water reservoir; a smoothly contoured handle comprising two parts, one of said parts being mounted on and above the base assembly for carrying and manipulating the iron, and having a vertical passage therethrough communicating with said reservoir, the other part being a movable grip section; means slidably mounting said grip section on said first part of the handle for forward horizontal movement to a first position in which it forms a smooth continuation of said first part and closes the upper end of said passage, and for rearward horizontal movement to a position exposing the upper end of said passage; a valve mounted on said handle within said passage and movable vertically between a first position in which the passage is interrupted by the valve and a second position in which the valve does not interrupt the passage; means interconnecting said grip section and valve for causing vertical movement of the latter to its first position in response to horizontal sliding of the grip section to its first position, and vertical movement to its second position in response to horizontal sliding of the grip section to its second position; and releasable latch

means for retaining said grip section in said first position.

15. In a steam iron, a base assembly including a heated sole plate and a water reservoir, said sole plate having a steam jet formed therein; a smoothly contoured handle comprising two parts, one of said parts being mounted on and above the base assembly for carrying and manipulating the iron, and having a vertical passage therethrough communicating with said reservoir, the other part being a movable grip section slidably mounted on said first part of the handle for forward movement to a first position in which it forms a smooth continuation of said first part and closes the upper end of said passage, and for rearward movement to a position exposing the upper end of said passage; a standpipe mounted on said base assembly, communicating with said jet, and extending upwardly into said passage; a valve mounted on said handle within said passage and movable between a first position in which the passage is interrupted by the valve just above the upper end of said standpipe, and a second position in which the valve does not interrupt the passage; means interconnecting said grip section and valve for causing movement of the latter to its first position in response to sliding of the grip section to its first position, and to its second position in response to sliding of the grip section to its second position; and releasable latch means for retaining said grip section in said first position.

16. In a steam iron, a base assembly including a heated sole plate and a water reservoir, said sole plate having a steam jet formed therein; a smoothly contoured handle comprising two parts, one of said parts being mounted on and above the base assembly for carrying and manipulating the iron, and having a vertical passage therethrough communicating with said reservoir, the other part being a movable grip section slidably mounted on said first part of the handle for forward movement to a first position in which it forms a smooth continuation of said first part and closes the upper end of said passage, and for rearward movement to a position exposing the upper end of said passage; a standpipe mounted on said base assembly, communicating with said jet, and extending upwardly into said passage; a valve mounted on said handle within said passage and movable between a first position in which the passage is interrupted by the valve just above the upper end of said standpipe, and a second position in which the valve does not interrupt the passage; means interconnecting said grip section and valve for causing movement of the latter to its first position in response to sliding of the grip section to its first position, and to its second position in response to sliding of the grip section to its second position; resilient means urging said valve to its first position, said one handle part having a vent opening communicating with said passage between said valve and the upper end of the passage; and releasable latch means for retaining said grip section in said first position.

17. In a steam iron an assembly comprising a heated sole plate and a water reservoir mounted above the sole plate, said reservoir having a filling opening; means providing a valve seat adjacent said filling opening; a valve mounted on said assembly and cooperable with said seat for closing said filling opening; resilient means urging said valve against said seat; a manually engageable and movable operator mounted on said

11

assembly; and means for moving said valve in response to movement of said operator including a cam having a plurality of sections operating in sequence, one of said sections being a sloping section for lifting said valve from said seat against the force of said spring, and another of said sections being a flat section for retaining said valve away from said seat against the force of said spring, whereby the valve is retained in open position away from said seat without the necessity for continuous manual pressure on said operator.

ARTHUR A. JOHNSON.
